UNITED STATES PATENT OFFICE

122,390

DESIGN FOR A COAT HANGER

Evelyn Daniels, San Francisco, Calif.

Application December 23, 1939, Serial No. 89,103

Term of patent 7 years

To all whom it may concern:

Be it known that I, Evelyn Daniels, a subject of King Gustaf of Sweden, residing at 1663 Bush Street, San Francisco, county of San Francisco, State of California, have invented a new, original, and ornamental Design for a Coat Hanger, of which the following is a specification, reference being had to the accompanying drawing, forming part thereof.

I claim:

The ornamental design for a coat hanger, as shown.

EVELYN DANIELS.
